UNITED STATES PATENT OFFICE.

GEORGE J. RATHBUN, OF TOLEDO, OHIO, ASSIGNOR TO INGERSOLL-RAND COMPANY, OF JERSEY CITY, NEW JERSEY, A CORPORATION OF NEW JERSEY, JOINTLY WITH THE RATHBUN-JONES ENGINEERING COMPANY, A CORPORATION OF OHIO.

DISTRIBUTOR FOR COMBUSTION ENGINES.

Application filed April 25, 1924. Serial No. 708,835.

To all whom it may concern:

Be it known that I, GEORGE J. RATHBUN, a citizen of the United States, and a resident of Toledo, county of Lucas, and State 5 of Ohio, have invented a certain Distributor for Combustion Engines, of which the following is a specification accompanied by drawings.

This invention relates to internal combustion engines and more particularly to devices for supplying fuel selectively to a plurality of cylinders without the admixture of air and purely mechanical.

Heretofore, in multi-cylinder engines of 15 the solid injection type, it has generally been the practice to provide each cylinder with an individual pump to inject the fuel. It is the object of this invention to provide a device which may be used in connection 20 with a multi-cylinder engine to distribute the fuel to the various cylinders in a predetermined order and which renders the use of a plurality of pumps unnecessary. The use of this device has a number of advantages among which may be mentioned 25 simplicity and consequent cheapness, and uniformity in the amount of charge supplied to each and all of the cylinders, and accuracy of timing of the supply of fuel 30 with respect to the operating cycle of the various cylinders. This device needing the use of only one pump produces these advantageous results. A single pump injects the fuel into all of the cylinders, which injection is certain to be like every other injection in amount and, if the conditions in each 35 of the cylinders are the same equal explosive force in the cylinders so that the engine will fire evenly and smoothly. A system using 40 this distributing device should be relatively inexpensive on account of the cheapness of a single fuel pump and distributing device as compared with the cost of a number of pumps, one for each cylinder, together with 45 the elimination of the plurality of driving gears for actuating the pumps. The timing of the fuel injection may be accurately predetermined by accurate construction of the distributing device, whereas the use of an 50 individual pump for each cylinder may re-

quire separate timing and adjustment of the driving connections therefor.

Other objects and advantages of the fuel distributor of this invention will become apparent from the following description taken 55 in conjunction with the drawings in which there is shown one form, which the invention may assume in practice.

Figure 1 is a side elevation in section of a fuel distributing device constructed in accordance with the practice of the invention, showing the driving connections therefor and one of the engine cylinders and fuel injection nozzle to be associated with the distributor;

Figure 2 is a top view with the cover plate of the distributor removed showing the driving gears on the line 2—2 of Figure 1 looking in the direction of the arrows;

Figure 3 is a plan view of the distributor head in section along the line 3—3 in Figure 1 looking in the direction of the arrows; and

Figure 4 is a horizontal section of the machine along the line 4—4 in Figure 1 looking in the direction of the arrows showing the connection at the main driving shaft.

The distributor is provided with a body A having a head B tightly fitted together to prevent the escape of fluid therebetween. An aperture C is provided in the body A to accommodate a rotatable disc D held against the lower face of the head B by means of a coil spring E, rotation of the spring being permitted by a convex bearing member F lying in the bottom of the aperture C. A 80 passage G extending into the body A is adapted to conduct fuel oil to the aperture C from a suitable source, preferably an injection pump of the type shown in copending application Serial No. 708,837, filed April 25, 1924. Such a pump is adapted to supply fuel intermittently under pressure there being periods at which the pressure drops to a negligible amount, although at the instant that it is desired to inject the fuel into the combustion engine cylinder the pressure is extremely high as, for instance, 1,000 lbs. per square inch.

The distributor is adapted to be used with an engine having more than one cylinder 100

and its purpose is, therefore, to complete a free and unobstructed passage from the source of fuel selectively to the injection nozzles at the cylinders. To this end, the 5 disc D is provided with a port H which, as the disc rotates is adapted to register successively with a plurality of ports J in the face of the head B an equal distance from each other and from the center of rotation of 10 the disc D. A passage K is provided for each of the ports J and leads to the exterior of the head B for connection with suitable pipes L leading to the injection nozzles O of the cylinders P. Only one of the cylinders 15 P is shown in the drawings, it being understood that the others are similar thereto.

As the disc D rotates, the port H registers successively with the ports J and remains for a moment with said ports in 20 registry. Means for producing such intermittent rotation of the disc D includes a shaft Q attached to the disc D by means of a key R or other suitable device and extending through the head B for connection with intermittent driving gears S and 25 T. The gear S is mounted for rotation on a sleeve U which is provided with a large aperture V to allow the shaft Q to rotate freely without possibility of interference 30 although said shaft may be out of alignment with the center of the sleeve U. The purpose of this is to insure that the contacting faces of the disc D and the head B will always be permitted to lie flat against 35 each other without external interference. The shaft Q is loosely connected with the gear S through the pin W mounted in a removable head X on the shaft Q, the pin W being loosely in engagement with a slot 40 Y cut in the rim of the hub Z formed integrally with the gear S. In order to hold the pin W in the slot Y a spring clip a passing through a groove b in the head X 45 grips the hub Z of the gear S at holes c. The clip a may be sprung off the head X so as to release the shaft Q and permit its removal.

The sleeve U is mounted in a frame d upon which the body A and head B are 50 supported. Suitable studs e pass through the body A and the head B and spacers f to hold the body and head firmly in position.

The intermittent driving gear T is journaled at a hollow bearing g mounted in the frame d. One form of intermittent driving gear which may be employed is shown in Figure 2 wherein the gear T is provided with teeth h which are placed relatively far apart as compared with the spacing of the corresponding teeth k on the driven gear S. The space between the teeth h is partly cylindrical as at p except close to the teeth h where it is cut away as at q. The ends 65 of the teeth h are cut to conform to the

cylindrical surface p on the gear T. Thus, as the gear T rotates, the tooth h meshes with one of the teeth k and rotates the gear S through an angle corresponding to two teeth k. After the tooth h is passed out of mesh with the teeth k, the cut away ends of the teeth h engage the cylindrical surface p of the gear T and the gear S is held stationary by said cylindrical surface until the next tooth h comes into mesh with the tooth k. The periphery of the gear being cut away at q, the tooth h is permitted to drop into the recess so formed and the gear S is thereupon rotated to a degree corresponding to two teeth k, the recess q on the rearward side of the tooth h permitting the end of the tooth h to pass. The number of teeth h on the gear T preferably corresponds to the number of cylinders in the engine. The number of teeth k on the gear S will be twice this number since each tooth h in passing meshes with two teeth of the gear S.

From the above description it will be seen that there is a period of rest in the gear S and consequently in the disc D followed by a rapid shift during the period of no pressure. The port H is arranged to be in registry with one of the ports J and it is at this time that the pumping stroke in the fuel injection pump should occur. The shifting of the disc D should be timed to occur during a period of substantially no pressure at the fuel source. One advantage of this arrangement is that there will be no pressure on the disc D while the disc is being rotated for the injection pressure is usually high and it would be difficult to rotate the disc D with the high pressure pressing it into contact with the face of the head B. It is for this purpose that the disc D is rotated intermittently and remains stationary while the injection pressure is applied.

The intermittent driving gear T is driven preferably through gears or similar means directly connected with the crank shaft of the engine so that the rotation of the disc D bears a fixed relation to the crank shaft rotation. In the case of a six cylinder, four-stroke cycle engine, the driving gear T should rotate at one half the crank shaft speed. Since this is the same speed at which the cam shaft for operating inlet and exhaust valves is driven, the gear T may be driven by gears such as the bevel gears r and s, the former being mounted on the cam shaft t, the latter upon a shaft u loosely connected with the gear T. The loose connection between the shaft u and the gear T comprises a key v (Figure 4) held in engagement with the end of the shaft u by means of a pin w and inserted in the slotted end x of the hub y of the gear T. A pin z insertable into the key v at

a notch 2 insures that the timing of the gears T will be correct. The key v, the shaft u and the hub y are held in position by a washer 3 and the nut 4 on the threaded end of the shaft u.

A cover 5 for the frame d is suitably recessed to act as a bearing for the gears S and T and is held in place by suitable studs 6 having nuts 7.

10 The frame d is preferably mounted on the engine base 8 by means of studs 9 and nuts 10. A suitable bearing for the shaft u is provided by the sleeve 11 in the engine base

15 8. Lubrication for the gears S and T may be provided through the holes 12 and 13 respectively, surplus oil from the interior of the hubs Z and y being permitted to drain through the apertures 14 and 15 respectively.

When initially setting the distributor, it 20 is desirable to be able to determine the position of the port H with respect to the ports J so as to properly time the injection of fuel into the cylinders. To this end there are 25 provided pins 16 mounted on the upper face of the head B corresponding to the position of the ports J, and an index 17 adjacent the pin 16, mounted on the shaft Q which together indicate the position of the port H with respect to the ports J.

30 I claim:

1. A fuel distributing apparatus for multi-cylinder internal combustion engines comprising the combination of a plurality of passages associated with corresponding cylinders, a source of fuel intermittently under pressure, means to connect the said source selectively with said passages, and means to shift said connecting means during periods of substantially no pressure in said fuel 35 source.

2. A fuel distributing apparatus for multi-cylinder internal combustion engines comprising the combination of a plurality of passages associated with corresponding cylinders, a source of fuel intermittently under pressure, means to connect said source selectively with said passages including a pair of relatively movable discs, one of said discs being provided with a plurality of 45 ports communicating with said passages and the other being associated with said source, and means to shift said connecting means during periods of substantially no pressure in said fuel source.

55 3. A fuel distributing apparatus for multi-cylinder internal combustion engines comprising the combination of a plurality of passages associated with corresponding cylinders, a source of fuel intermittently under pressure, means to connect said source selectively with said passages including a pair of relatively movable discs, one of said discs being provided with a plurality of ports 60 communicating with said passages and the other being associated with said source, and

intermittent gearing to shift said connecting means during periods of substantially no pressure of said fuel source.

4. A fuel distributing device for multi-cylinder internal combustion engines comprising the combination of a body portion, a head on said body portion provided with ports leading to the cylinders of said engine, an intermittently rotatable disc within said body portion having a port adapted to register with the ports in said head in a predetermined order, and means for holding said disc against said head.

5. A fuel distributing device for multi-cylinder internal combustion engines comprising the combination of a body portion, a head on said body portion provided with ports leading to the cylinders of said engine, an intermittently rotatable disc having a port adapted to register with the ports in said head, and a shaft associated with said disc extending through said head.

6. A fuel distributing device for multi-cylinder internal combustion engines comprising the combination of a body portion, a head on said body portion provided with ports leading to the cylinders of said engine, an intermittently rotatable disc within said body portion having a port adapted to register with the ports in said head in a predetermined order, a shaft associated with the said disc extending through said head, and intermittent driving gears for rotating said shaft in a flexible connection between one of said gears and said shaft.

7. A fuel distributing device for multi-cylinder internal combustion engines comprising the combination of a body portion, a head on said body portion provided with ports and passages extending radially therefrom leading to the cylinders of said engine, an intermittently rotatable disc having a port adapted to register with the ports in said head in a predetermined order, and a shaft associated with said disc extending through said head.

8. A fuel distributing device for multi-cylinder internal combustion engines comprising the combination of a body portion, a head on said body portion provided with ports and passages extending radially therefrom leading to the cylinders of said engine, an intermittently rotatable disc on the said body portion having a port adapted to register with the ports in said head in a predetermined order, a shaft associated with said disc extending through said head, and intermittent driving gears flexibly connected with said shaft.

9. A fuel distributing device for multi-cylinder internal combustion engines comprising the combination of a body portion, a head on said body portion provided with ports and passages extending radially therefrom leading to the cylinders of said engine,

an intermittently rotatable disc within said body portion having a port adapted to register with the ports in said head in a predetermined order, a spring holding said disc against said head, a bearing member permitting rotation of said spring with said disc, a shaft associated with said disc extending through said head, intermittent driving

gears for rotating said shaft, a flexible connection between one of said gears and said shaft, and a driving shaft for the other said gears being loosely connected to said shaft. 10

In testimony whereof I have signed this specification.

GEORGE J. RATHBUN.
